SHOE SUPPORT

Joel B. Wells, 650 S. Highland Ave., Merion, Pa.; Richard Wells Wilby, executor of said Joel B. Wells, deceased

Filed Aug. 6, 1956, Ser. No. 602,266

10 Claims. (Cl. 211—35)

This invention relates to shoe supports, and more particularly to novel apparatus for supporting shoes in a fixed position.

The apparatus according to the invention provides important advantages with regard to the security of holding the shoes in place and with regard to ease of placing shoes in position in, and removing shoes from, the support, these features being obtained together in a superior manner in the apparatus according to the invention.

The invention will be more fully described in connection with the attached drawing, in which Figures 1 and 2 are side and front views respectively of one embodiment of apparatus according to the invention, Figures 3 and 4 are side and front, partial views of a second embodiment, Figures 5 and 6 are side and front, partial views of a third embodiment, Figure 7 is a front view of a fourth embodiment, Figure 8 is a front view of a fifth embodiment, and Figure 9 is a partial front view of a sixth embodiment.

Referring to Figures 1 and 2, a metal plate 10 is secured to a vertical wooden support 11 by means of screws 12. Coil spring sections 13 are rigidly secured at their outer ends 14 to the plate 10, as for example, by soldering or other suitable means. Metal rods 15 are secured to the spring 13, and may be integral therewith. The rods 15 are rigidly secured also to plate or shank 16. As shown, rods 15 are connected with each other by means of a rod 17, integral with the rods 15 and rigidly secured, as by welding or other suitable means, within a turned-under portion 18 of plate 16. In the device as shown, the spring sections 13, the rods 15, and the rod 17 are constructed of a single metal wire; however, this construction is not essential. The rods 15 and the plate 16 constitute together a shank secured at one end to the spring means 13 and adapted to be urged toward the surface 11 by those spring means.

Rods 23 are secured to plate 16 by means of rod 19, integral with rods 23; rod 19 is rigidly secured within turned-under portion 20 of plate 16. Rods 23 extend laterally away from the longitudinal axis of plate 16 and also extend toward surface 11. Rods 23 are rigidly secured at their lower ends to shoe engaging means provided by the wire loops 21. Rods 23, rod 19, and loops 21 may if desired be constructed of a single metal wire, as shown; however, this construction is not essential. Loops 21, which are secured to the shank provided by plate 16 by means of rods 23 and 19, are adapted to hold, under the influence of spring means 13, the shoes 22 in vertical position with their soles against surface 21. Suitable cloth or other pads not shown can be secured to loops 21 to protect the shoes if necessary.

The loops 21 constitute shoe engaging means adapted to engage the soles of shoes 22, and are secured to shank 16 by means of connecting rods 23, which are substantially normal to the plane of the loops 21 and to the sole of the shoes 22. The loops can if desired be curved to conform to the shape of the sole of the shoe. Arcuate,

2

rather than closed, loops can be employed if desired. Plates rather than loops can be employed if desired.

When the shoes 22 are not in place, the spring means 13 hold the loops 21 flat against surface 11. In order to put the shoes in position, one grasps the plate 16, pulls the lower end thereof away from surface 11, places the shoes in the positions indicated in Figure 1, and releases the plate 16, so that the spring means 13 press the loops 21 against the soles of the shoes.

Turning now to Figures 3 and 4, a different construction is shown for that part only of the apparatus which is attached to the lower end of shank 16. Metal rod 30 has a central portion 31 which is pivotally secured within a turned-under portion 20 of shank 16 and has side portions 32 which extend toward vertical surface 11 and also laterally away from shank 16 as viewed in Figure 4. The rod 30 also has portions 33 which extend upwardly, in a direction generally parallel to surface 11. Secured to the upper ends of portions 33 are shoe toe engaging heads 34, which are shaped in such manner as to stretch the toes of the shoes in which they are inserted. Any suitable known construction for toe engaging heads can be employed.

As illustrated, when shoes are not in place in the apparatus, the heads 34 are held flat against surface 11 by spring means 13. To place shoes in position, the shank 16 is pulled away from surface 11, and portion 31 of rod 30 pivots within portion 20 of shank 16 under the influence of gravity and/or manual pressure, thus permitting shoes to be placed in the desired position with their soles against surface 11. The spring 13 is then allowed to force shank 16 toward surface 11, the heads 34 meanwhile being inserted in the toes of the shoes.

Instead of the rod portions 32 being integrally connected to each other through portion 31, the portions 32 can be independently pivotally connected to shank 16, so that one of the portions 32 can be pivoted while the other remains stationary. However, highly satisfactory operation can be obtained with the simpler construction described above.

In the apparatus shown in Figures 3 and 4, each head 34 is connected to shank 16 by means of rod portion 33 which constitutes a rod extending downwardly from head 34, and by means of rod portion 30 which constitutes a second rod secured to the shank and to the rod portion 33 at the latter's lower end.

Toe engaging heads such as the heads 34 can be employed with either a rigid connection to shank 16 as in Figures 1 and 2 or a pivoted connection to shank 16 as in Figures 3 and 4. Similarly, shoe engaging members such as the loops 21 can be employed with either a rigid or pivotal connection to shank 16. A pivotal connection is preferred because it provides greater ease of manipulation.

Turning now to Figures 5 and 6, a variation of the apparatus shown in Figures 1 and 2 is illustrated therein, the two shanks 50 replacing the single shank 16 of Figures 1 and 2. Each shank 50 is rigidly secured to connecting member 51, to which the rods 15 are also secured.

The rods 15 are also secured, as shown in Figures 1 and 2, to the spring means 13. With this construction, the rods 50 can be sufficiently flexible to permit some flexing of the rods 50 to facilitate placing the shoes therebeneath, but they are not so flexible as to be incapable of transferring the force exerted by spring means 30 to shoe engaging members, through connecting rods 52, sufficiently for that force to hold the shoes against surface 11. Substantially nonflexible shanks can, of course, be employed if desired.

In Figure 7, spring 13 is rigidly secured to a plate 10 by means of a screw 72 which bears upon looped section 71 of the spring, section 71 being formed by curving the

spring-wire down to the plane of plate 10 and around in that plane to form the loop. Integral shanks 70 extend downwardly from the outer ends of the spring 13. Suitable shoe engaging members, not shown, are attached to the lower ends of each shank 70. The shoe engaging members illustrated in other figures are examples of suitable members that can be used with the apparatus of Figure 7.

The various parts of the shoe supports according to the invention can if desired be made integral with each other. Thus, referring to Figure 8 the spring 13, the shank 16, and the shoe engaging member 21 can be constructed of a single wire 40 suitably shaped to provide the desired construction and relationship of the parts to each other. Also, the outer ends of the spring can be shaped into a loop 41 in a plane parallel to the plane of surface 11, so that the spring can be directly attached to the surface 11 by screws 12 inserted through the loops at either end.

If desired, a plurality of the shoe supports according to the invention can be secured to a flat surface, e.g., a metallic or wooden surface, to provide a shoe rack adapted to hold a plurality of shoes and to be placed in any suitable location, e.g., against a wall or door, etc.

It is not essential, according to the invention, that the surface 11 be a vertical surface, since the invention is applicable to horizontal or inclined surfaces also. However, the maximum utility and convenience of the invention is obtained where the surface is substantially vertical, or at least inclined more to the vertical than to the horizontal.

It is not essential that the shoe be held by the apparatus according to the invention with its toe toward the spring 13, since the invention is applicable to arrangements where the heel or other portion of the shoe is closest to the spring. However, superior results are obtained with the arrangement illustrated in the drawing.

It is not essential that the surface to which the spring 13 is attached and the surface against which the shoe is held should lie in the same plane, though such arrangement, as shown in the drawing, is preferred.

If desired, the apparatus shown in Figures 1 and 2 can be modified by providing, as shown in Figure 9, in each of the members 23 a coiled, spring section adjacent the connecting member 19 which is rigidly secured to shank 16. Such spring sections and the members 19 and 23 can be constructed, for example, from a single wire 42 by tightly coiling the wire in two portions 43 thereof separated by the central portion 19, the outer uncoiled portions of the wire constituting the members 23. In operation, the member 23 and shank 16 can be moved in relation to each other by exerting manual pressure, thus facilitating insertion and removal of shoes. In the absence of such pressure, the spring sections hold the members in the desired relationship to each other.

The invention claimed is:

1. A shoe holder which comprises: spring means secured to a support; connecting means comprising shank means secured at one end to said spring means and extending therefrom, and two portions mounted on said shank means and extending laterally toward said support; two shoe-engaging members connected to the ends of said portions and urged toward said support by said spring means to hold, solely by the lateral force of said

spring means exerted through said members, two shoes in fixed positions with their soles against said support.

2. Shoe holder according to claim 1 wherein said shank means consist of a single shank.

5 3. Shoe holder according to claim 1 wherein said shank means consist of two shanks, to each of which shanks one of said shoe-engaging members is connected.

4. Shoe holder according to claim 3 wherein a portion of said spring means, one of said shanks, a connecting rod and one of said shoe-engaging members are constructed of a single wire, and wherein the remaining portion of said spring means, the other of said shanks, a second connecting rod and the other of said shoe-engaging members are constructed of another single wire.

10 5. Shoe holder according to claim 1 wherein said shank means and said shoe-engaging members are rigidly connected to each other by means of connecting rods.

6. Shoe holder according to claim 1 wherein a connecting rod is rigidly secured to each of said shoe-engaging members and pivotally connected to such shank means, and wherein each of the two connecting rods extends outwardly from the shoe-engaging member to which it is attached, whereby the pivotal connection of the connecting rod to the shank means facilitates introduction of 20 and removal of the shoe-engaging member from a shoe.

25 7. Shoe holder according to claim 1 wherein each of said shoe-engaging members comprises a member adapted to engage the sole of said shoe over an extended area, said area being the only area of contact of said member with the shoe.

8. Shoe holder according to claim 1 wherein each of 30 said shoe-engaging members comprises a toe-engaging head connected to said shank means by a connecting rod having a portion secured at one end to the rear of said head and extending toward the heel of the shoe and a second portion substantially perpendicular to the first portion and secured to said shank means and to the other end of said first portion.

9. Shoe holder according to claim 1 wherein the shank 35 means extend straight from their junction with the spring means to their junction with the connecting rods attached to said shoe-engaging members.

10. Shoe holder according to claim 1 wherein a coil is 40 provided in each of two connecting rods secured to said shank means, the coils being disposed on either side of and adjacent to said shank means and wherein a shoe-engaging member is secured to each of said rods.
